Specification for Design.

Patented Nov. 28, 1916.

Application filed October 25, 1915. Serial No. 57,890. Term of patent 14 years.

To all whom it may concern:

Be it known that I, JOSEPH E. LEONARD, a citizen of the United States, residing at Cedar Rapids, in the county of Linn and State of Iowa, have invented a certain new, original, and ornamental Design for Stoves and Ranges, of which the following is a specification.

The design is fully illustrated in the single figure of the accompanying drawing, in which an elevated oven range is shown in front, diagonal perspective.

Copies of this patent may be obtained for five cents each, by addressing the "Commissioner of Patents, Washington, D C."

Witnesses:

L. BROMWELL,
J. M. ST. JOHN.

I claim:

The ornamental design for a stove or range substantially as shown.

In testimony whereof I affix my signature in presence of two witnesses.

JOSEPH E. LEONARD.
